UNITED STATES PATENT OFFICE.

WILLIAM F. DITLEVSON, OF OWATONNA, MINNESOTA.

DOOR-LOCK.

1,197,612.

Specification of Letters Patent. Patented Sept. 12, 1916.

Application filed September 18, 1915. Serial No. 51,374.

To all whom it may concern:

Be it known that I, WILLIAM F. DITLEVSON, a citizen of the United States, residing at Owatonna, in the county of Steele 5 and State of Minnesota, have invented certain new and useful Improvements in Door-Locks, of which the following is a specification.

My invention relates to improvements in locks for doors of out-buildings as an automobile garage, its object being to provide a door which can only be locked or unlocked from a house at some distance away, thus preventing unauthorized entering of the 15 garage.

To this end the invention consists in the features of construction, combination, and arrangement of parts hereinafter described and claimed.

In the accompanying drawings forming 20 part of this specification, Figure 1 is a view of a garage door from the inside, with the surrounding wall partly broken away showing my features of invention applied to the 25 door and shown in connection with the house; Fig. 2 is a detail view of the end of a slidable locking rod forming part of my invention; and Fig. 3 is a detail view of a modification of a portion of the construction 30 for adapting the invention to being operated from a position at an angle with the door.

Referring to the drawings 2 and 3 represent a pair of ordinary swing doors, the 35 door 2 being formed with hand operated locking bolts 4 and 5. Mounted upon the inner face of the door 3 is a horizontal rod 6 slidable in brackets 7. The inner end of the rod 6 has pivotal connection 8 with the 40 adjacent end of the toggle arms 9 and 10, the upper and lower ends of the toggle arms 9 and 10 respectively being pivotally connected with bolts 11 and 12 slidable through brackets 13 into openings in, the 45 top and bottom of the surrounding frame of the door, whereby to lock the door when closed.

For the purpose of actuating the locking bolts 11 and 12 and supported parts there- 50 for I provide the following mechanism: Slidable through the door frame adjacent the hinged edge of the door 3 is a rod 14, the inner end of the rod 14 being flattened and formed with a side opening 15. The 55 outer end of the rod 6 is formed with a

slot 16 and vertical pin 17. Thus with the toggle arms 9 and 10 and the rods 6 and 14 standing in the position shown in Fig. 1, the door when closed will bring the pin 17 into the opening 15 with the flattened end 60 of the rod 14 into the slot 16, leaving the rods 6 and 14 locked together to allow sliding movement, and allowing separation of the rods 6 and 14 as the door is opened. The outer end of the rod 14 is pivotally 65 connected with the upper end of the lever arm 18, which lever arm has fulcrum support 19 and at its lower end is connected by a rod 20 and rod 21 with an actuating lever arm 22 located in the house. The rods 70 20 and 21 pass from the garage to the house in concealed position as under ground. The rods 20 and 21 are used when the house is laterally in line with the door. When the house is at the front or rear of the garage, 75 a bent lever arm 23 may be suitably fulcrumed between the rods 20 and 21 so that the cable can pass from the bent lever arm 23 either rearwardly or forwardly to the house.

In operation, the parts being moved to the position shown in Fig. 1 by the lever arm 22 will allow the door 3 to be pushed open, allowing a person to enter the garage and by hand unlock and open the door 2. 85 When it is desired to close the garage the door 2 will be locked in the ordinary way in closed position and the door 3 closed to bring the flattened end of the rod 14 into the slot 16 with the pin 17 extending 90 through the opening 15. By then pulling the lever arm 22 inwardly the rod 6 will be shoved inwardly upon the door to straighten the toggle arms 9 and 10 and shove the bolts 11 and 12 into the openings therefor 95 in the framework above and below the door. It thus will be evident the door can only be locked or unlocked from inside the house and that all connections between the locking lever in the house and the locking mechanism upon the door may be concealed as by being passed to the house under ground.

I claim:

1. In combination with a hinged door, a locking bolt slidable upon the face of the 105 door in coöperation with the surrounding frame, an actuating bar, for said locking bolt slidable upon the door, an actuating bar for said first mentioned bar slidable through the surrounding framework of the 110

door, an actuating lever, and a rod and lever connection between said bar and actuating lever.

2. Means for actuating the locking mechanism of a hinged door from a point some distance away, comprising locking bolts 5 slideable upon the face of the door, an actuating bar therefor slideable through the surrounding framework of the door, an actuating lever arm at a removed point, and an under ground connection between said toggle arm actuating bar and said lever arm.

3. Means for actuating the locking mechanism of a door from a removed point, comprising in combination a door, locking bolts 10

slidable upon the face thereof; separable actuating rods for said locking bolts comprising one rod slideable upon the face of the door and a rod removably interlocking therewith and slideable through the surrounding framework of the door, an actuating lever arm at a removed point and an under ground connection between said lever arm and said rods.

In testimony whereof I affix my signature in presence of two witnesses.

WILLIAM F. DITLEVSON.
